UNITED STATES PATENT OFFICE

154,119

DESIGN FOR A HANDBAG

Edgar F. Gumbrell, Walsall, England, assignor to Greatrex Ltd., New York, N. Y., a corporation of New York

Application May 29, 1948, Serial No. 146,693

Term of patent 14 years

(Cl. D87—3)

To all whom it may concern:

Be it known that I, Edgar F. Gumbrell, a subject of the King of Great Britain, of No. 118 Walsall Street, in the city of Walsall, county of Staffordshire, and Kingdom of Great Britain, have invented a new, original, and ornamental Design for Handbags, of which the following is a specification, reference being had to the accompanying drawing, forming part thereof.

Figures 1 and 2 are respectively side and end views of a handbag, showing my new design.

I claim:

The ornamental design for a handbag, as shown.

EDGAR F. GUMBRILL.
